United States Patent Office

Des. 187,536
Patented Mar. 29, 1960

187,536

TELEPHONE SHELF

Carysfort F. Lloyd-Young, Seattle, Wash.

Application November 24, 1958, Serial No. 53,509

Term of patent 3½ years

(Cl. D33—3)

Fig. 1

Fig. 4

Fig. 2

Fig. 3

Fig. 1 is a perspective view of a telephone shelf showing my new design.

Fig. 2 is a side view of the shelf taken from the right of Fig. 1.

Fig. 3 is a front view of the shelf, showing in dash lines, for illustrative purposes only, the positions of the telephone and its receiver when applied thereto.

I claim:

The ornamental design for a telephone shelf, as shown and described.
